US00D649973S

(12) **United States Design Patent**
Matas

(10) Patent No.:

US D649,973 S

(45) Date of Patent: ** Dec. 6, 2011

- (54) **GRAPHICAL USER INTERFACE FOR A DISPLAY SCREEN OR PORTION THEREOF**

D582,934 S 12/2008 Byeon
 D587,720 S 3/2009 Noviello et al.
 7,509,579 B1 * 3/2009 House et al. 715/714
 D590,410 S 4/2009 Wall et al.

(Continued)

- (75) Inventor: **Mike Matas**, San Francisco, CA (US)

- (73) Assignee: **Apple Inc.**, Cupertino, CA (US)

(**) Term: 14 Years

(21) Appl. No.: 29/375,796

(22) Filed: Sep. 27, 2010

Related U.S. Application Data

- (62) Division of application No. 29/317,755, filed on May 6, 2008, now Pat. No. Des. 624,555.

(51) LOC (9) Cl. 14-04
(52) U.S. Cl. D14/486
